CONTROL DEVICE

Earnest J. Dillman, Detroit, Mich., assignor to
Detroit Lubricator Company, Detroit, Mich., a
corporation of Michigan

Application June 17, 1930, Serial No. 461,669

26 Claims. (Cl. 236—92)

My invention relates to new and useful improvements in control devices, and more particularly to a device or apparatus having one or more means for automatically regulating or controlling one or more control devices in response to predetermined conditions or changes of conditions, such that certain mechanism or apparatus in connection with which the control device or devices is or are employed, will be controlled or regulated in a desired manner. While it is evident that the control apparatus of my invention is capable of use with or embodiment in a multiplicity of different systems or apparatus, I have chosen, for the purpose of these specifications, to disclose the same in cooperable relation with a refrigerating system or apparatus, preferably of the absorption type, the cycle of operation of which is well known in the art.

The invention consists in the improved construction and combination of parts and their aggroupment in operative relation, all to be more fully described hereinafter, and the novelty of which will be particularly pointed out and distinctly claimed.

In the accompanying drawings, to be taken as a part of these specifications, I have fully and clearly illustrated a preferred embodiment of my invention, in which drawings:

Figure 1 is a view in front elevation, partly diagrammatic, having certain parts broken away, and being partly in vertical section, of an apparatus embodying my invention;

Fig. 2 is an enlarged detail view, partly in vertical central section, of my control device shown in Fig. 1, but with the cover or closure member thereof removed;

Fig. 3 is an enlarged detail view in vertical section, of part of the control device, and

Fig. 4 is an enlarged detail view of a part of an element of the control device.

Referring to the drawings by characters of reference, there are in the system or apparatus (Fig. 1) a generator-absorber A, a condenser B, a refrigerant reservoir C, a flow control means D, an evaporator E, and my control device or apparatus F, all connected in operative relation, as will be described.

The generator-absorber A comprises a housing or casing member 1 with insulated side walls, and having a top and a bottom wall 2, 3, respectively. In the top and bottom walls are preferably two outlet and two inlet openings 4, 4^a and 5, 5^a, respectively, which are preferably at the sides of the member 1 and extend completely from front to rear thereof. The interior of member 1 is

preferably divided into vertical flow passages 6, 7 and 8 by partitions, or the like, 9, 10 which terminate short of the top and bottoms walls, and which are in the respective planes of the substantially alined openings 4, 5 and 4^a, 5^a. Control means 11, such as dampers, flap valves, or the like, are provided for each of the openings 4, 4^a and 5, 5^a, which, when in open position, cooperate with the partitions to close the passages 6 and 8, and which when in closed position provide for circulation from passage 7 to passages 6 and 8 and then back to passage 7, as is apparent from Fig. 1. The means 11 are preferably carried by rotatable shafts journaled in the member 1 and having any suitable interconnecting linkage 12, whereby the means 11 are movable in unison to open and to closed positions. Within the passage 7 is a sealed container means 13, which preferably comprises a plurality of vertically positioned steel tubes having headers, or the like, 14 at top and bottom, the top header alone being shown, and which contains or is adapted to contain an absorbent or adsorbent medium, such, for example, as silica gel, or the like, designated 15. Sealed to and extending from the top header 14 is a conduit member 16 serving as a common delivery and return duct. In the bottom wall 3 is an aperture 17 positioned beneath means 13 for admission to the interior of member 1 of a heating means 18, preferably a gas or other fluid fuel main burner means supplied from any suitable source by a conduit member 19 having therein a flow control device or valve means 20, to be further described. The burner means 18 is preferably provided with a pilot burner 21 fed through a valve controlled conduit member 22 connected to member 19 on the supply side of means 20. Supported by the top wall 2 is a drive means 21, preferably an electric motor, having its drive shaft 23 vertically positioned and extending at its lower end through the wall 2 into passage 7. On the top and bottom ends of the shaft 23 are secured fan means 24, 25, respectively, for creating a forced gas flow. A vent pipe 26 opening from passage 8 to atmosphere is preferably provided.

Supported on top of the casing member 1 is the condenser B, preferably of the air cooled type, which is positioned directly over the fan means 24 and which is mounted on a housing 27 for the fan means 24. The housing 27 has inlet openings 27^a at front and rear below the means 24, so that cooling air or gases will be drawn into the housing by the means 24 and forced up through and over the condenser B. Extending from the top

inlet end of the condenser B is a conduit member 28 which connects into a valve casing 29 and through a check valve 30 therein to the conduit member 16, the valve 30 opening toward the condenser B.

From the lower outlet end of the condenser B extends a conduit member 31 in which is a check valve 31^a closing toward the condenser B and which leads to the flow control means D. Positioned in the conduit member 31 is the refrigerant medium receiver C. The means D is preferably a float valve such, for example, as that disclosed and claimed in the patent to Lewis W. Eggleston, No. 1,832,693, granted November 17, 1931.

From the means D leads a conduit member 32 to the evaporator E, from which passes a conduit member 33 to the valve casing 29 and through a check valve 34 therein to the conduit member 16, the valve 34 opening toward the member 16. The refrigerant medium which passes through conduit members 16, 28 and 33 is substantially in the vapor state, and these members are therefore preferably of larger diameter bore than members 31 and 32 which convey the medium in liquid state.

Mounted on brackets, or the like, on the front wall of member 1, is the control device F, which preferably has a substantially rectangular supporting framework 34^a having top and bottom frame members 35, 36 and end frame members 37, 38. Rigidly secured in an aperture in the bottom member 36 and depending therefrom, is the valve means 20 having a port 39 with which cooperates a reciprocable valve member 40 carried by a stem 41 having a sliding fit in and extending up through a guide aperture in the valve bonnet 42. Between and secured to the top and bottom members 35, 36 is a substantially vertical supporting frame member 43 having a horizontal guide aperture 44 therethrough adjacent its mid-portion. Extending through the aperture 44 is a reciprocable thrust member or plunger 45 carrying thereon a slideable sleeve member 46, preferably of brass, having guided bearing in the aperture 44. Intermediate its ends the plunger 45 is screw threaded and adjustably carries an operating nut or trip member 47 for a purpose to be described, and which also serves to limit movement of said sleeve member 46 in one direction. Movement of member 46 in the opposite direction is limited by a collar or stop member 48 rigid with plunger 45, and preferably seated in a circumferential groove therein. Movable relative to member 46 and carried thereby, is an abutment or operating member 49, preferably an annulus of hardened tool steel having sharp, marginal edges on its inner circumference, as at 50, 51 (see Fig. 3). The member 49 is of slightly larger internal diameter than the external diameter of member 46, so that when tilted from a plane substantially normal to the longitudinal axis of plunger 45, the edges 50, 51 of member 49 will bite into member 46 and cause member 49 to move positively therewith. Normally acting on the member 49 is a resilient means 52 tending to slide member 49 along member 46 from left to right of Figs. 2 and 3 and toward frame member 38. The means 52 is preferably a leaf spring member fixed, as at 53, to frame member 43 and bifurcated at its upper free end so as to pass to each side of member 46 and engage abutment member 49 at opposite points adjacent its horizontal diameter. Extending rigidly from frame member 43 toward frame member 38 below and

substantially equidistant laterally from member 46, are supporting arm members 54 having a substantially horizontal bearing pin or rod member 55 extending rigidly therebetween. Pivotally supported on pin 55 is a lever member or means 56 extending toward frame member 38 and having substantially parallel, horizontally spaced arm portions 57, 58 through which are alined bearing apertures 59 receiving the pin 55. Connecting the portions 57, 58 is a transverse or base 10 portion 60 from the top and bottom edges of which members 61, 62, respectively, extend toward frame members 38 in substantially parallel relation. The members 61, 62 extend through an aperture 63 in a substantially vertical bracket member 64. The bottom edge 65 of aperture 63 cooperates with member 62 to limit or stop downward movement of means 56. The arm portions 57, 58 are joined above pin 55 by a pin or rod 66 which is positioned just under sleeve member 46 and for engagement by the abutment member 49 upon its movement from left to right of Figs. 2 and 3. At its top the bracket member 64 has a lateral extension or arm 67 which overlies the member 61 and through which is adjustably 25 threaded a stop screw 68 cooperable with member 61 for regulating and limiting the permissible upward movement of means 56. Extending in prolongation of and substantially horizontally from the top of arm portion 57, is an operating arm or member 69 which passes through an aperture 70 in end frame member 38, and has pivotally secured on its free end, as at 71, and adjustably link or rod 72 which connects to the damper operating linkage 12, and preferably to one of 35 the inlet opening damper shafts. Also fulcrumed on pin 55 between arm portions 57, 58, is a lever or lifting member 73, preferably comprising substantially parallel rigidly connected arms 74 of substantially triangular form, having their bases 40 preferably substantially vertical and their apices apertured to receive the pin or shaft 55. The upper ends of arms 74 extend on opposite sides of plunger 45 and in proximity thereto, and terminate in fingers or trip members 75 substantially 45 at or above the contact points between leaf spring 52 and member 49 for engagement with the abutment member 49 to disengage the same from biting engagement with sleeve member 46. The member 73 also acts upon upward counter-clockwise movement about pin 55 to engage pin 66 subsequent to engagement of fingers 75 and members 49 to lift or rotate lever means 56 counterclockwise of Fig. 2. In opposing relation to the stop member 62 which extends beyond member 61, is a substantially horizontal lever member 76 which extends over the valve stem 41 and freely through an aperture 77 in frame member 38. The member 76 is provided with knife-edge fulcrum portions 78 which engage the inside face 60 of member 38. Interconnecting and pivoted to the member 76 and stem 41 is a link, or the like, 79 which serves to transmit motion from member 76 to the valve member 40. The members 62 and 76 terminate in conical points 80, 81, respectively, which seat in bearing recesses in spring follower members 82, 83 between which and held under compression thereby is a resilient means 84, preferably a coil spring. The screw 68 is preferably so adjusted and the length of link 79 is 70 such that when the lever means 56 is in upper position and valve 20 is closed, as in Fig. 2, the point 80 will be very slightly above the line of points 55 and 81, that is, the toggle joint will be broken upward slightly. Rigidly supported on 75

the lever member 76 and extending at an inclination upward therefrom, is an abutment arm 85. Secured to and depending from the top frame member 35 are supporting arms 86 between 5 which is fulcrumed, on a bearing pin 87, a lever member 88, which extends over the abutment arm 85 and from which depends a rod member 89 cooperable with arm 85 to depress the same. Positioned between members 35 and 88 is a coil 10 spring, or the like, 90 under compression and normally tending to force member 89 into engagement with arm 85 to close valve 20. The spring 90 is opposed and normally held inactive by pilot burner responsive means 91 which has a 15 bulb element 92, see Fig. 1, charged with a heat responsive medium and positioned to be heated by the flame of pilot burner 21. Extending from element 92 is a conduit 93 which connects into casing 94 secured to the top frame member 35 20 above lever member 88 and on the opposite side of its fulcrum from spring 90. The casing 94 is sealed by resilient means (not shown), such as a metal bellows, which carries a plunger 95 engaging the lever member 88 on the opposite side 25 of its fulcrum from spring 90 so that the presence of a proper pilot burner flame will maintain member 89 in the position of Fig. 2. Pivotal secured between the lifting member arms 74 at 30 their lower ends and on a pin 96, is a depending plunger 97 extending through a spring adjustment nut 98 and an aperture in the bottom frame member 36. Fixed to the underside of member 36 is the power element 99 of a means responsive to variation in a fluid characteristic, preferably 35 temperature, and which comprises a casing 100 sealed by resilient means 101, preferably a metal bellows, having fixed thereto a plunger 102 operatively connected to plunger 97. Within the bellows 101 around plunger 102, is a coil spring, or 40 the like, 103 under compression and which seats against the bellows head and the nut 98, and by which the response of the responsive means may be regulated. Leading from the chamber 104 within the casing 100, is a conduit 105 having 45 sealed to its free end a bulb element, or the like, 105^a charged with a suitable expansive medium and positioned within the generator-absorber passage 7, so that upon occurrence of a predetermined temperature or variation in temperature 50 of the heating gases in passage 7, the element 99 will be actuated to force the plunger 97 and lifting member 73 upward. Secured to the end frame member 31 is a power element 106 having a casing 107 within which is a plunger 108 in 55 substantial alignment with plunger 45 and operatively connected thereto. The plunger 108 is carried by resilient means 109, preferably a metal bellows, which seals the casing 107. Within the bellows 109 is a coil spring 110 under compression and surrounding plunger 108 and seating against the head of bellows 109. At its other end the spring 110 abuts an externally threaded apertured nut 111 which is adjustably screwed into 60 the frame member 31. The element 106 comprises part of a means responsive to variation in a fluid characteristic, preferably pressure, and has a conduit 112 connecting the chamber 113 within the casing 107 to the refrigerant medium return conduit member 33. Positioned on the 65 top of the top frame member 35 is an electric switch means 114, preferably of the enclosed contact tilting mercury tube type having terminals 115, 116 extending through the wall of the tube 117 and from which lead conductors 118, 119 to 70 the fan motor 21. The switch tube 117 is held in 75

a clip member 120 which is pivotally supported on a pin 121 carried by a bracket 122 to permit rocking or tilting movement of the tube to flow the mercury to and from the contacts. The tube 117 is counterweighted by a member 123 which 5 tends to maintain the motor circuit closed. Projecting from the clip member 120 is a lug 124 in the path of movement of one end of a lever arm 125 which passes downward through an aperture 126 in the top frame member 35, and which is 10 fulcrumed intermediate its ends on a bracket supported pin 127. The other end of arm 125 extends to the left of and into cooperable relation with the plunger carried trip member 47, so that movement of plunger 45 from right to left 15 of Figs. 2 and 3 acts to break the circuit of motor 21 within tube 117.

The operation of my control device or apparatus as embodied, for example, in a refrigerating system of the absorption type, will now be 20 described, it being understood that the control device is capable of embodiment in other systems and for controlling other means. In the drawings, the positions of the various elements of the system are such as occur on the completion of a heating cycle, and after the generator-absorber A has been cooled somewhat. Continuing from this point in a cycle of operation, the functioning of the system under command of my control device is as follows: The heat given 25 off from the container means in passage 7 will cause a natural upward flow of cooling gases or air in passage 7, which cooling air enters at inlet openings 5, 5^a and leaves via outlet openings 4, 4^a, the damper means 11 being in the positions 30 shown and the main burner 18 having been extinguished. The temperature at the evaporator E will be above the predetermined low limit for which the power element 106 is set, and therefore pressure of the vaporized refrigerant medium, 40 such, for example, as sulphur dioxide, in the conduit member 33 acting on the resilient chamber sealing means 109 will have moved the interconnected plungers 108 and 45 to the right of Figs. 2 and 3 at the start of the now completed heating cycle. The plunger 45 carries the nut or trip member 47 which on movement of plunger 45 to the right of Figs. 2 and 3 will have released 45 switch tube 117, permitting the weight member 123 to tilt the same clockwise on its pivot 121 to 50 energize the fan motor 21. The fan 25 driven by motor 21 will create a forced upward draft through passage 7, increasing the rate of cooling of the generator-absorber and container means 13. The cooling of the means 13 will reduce the 55 pressure therein, causing the liquefied refrigerant medium in the evaporator E to vaporize and pass back through conduit member 33, the check valve 34 and conduit member 16 to the container means 13, for absorption or adsorption 60 by the medium 15 therein. As the evaporator cools, due to the vaporization of the refrigerant medium, the pressure characteristic of the vaporized refrigerant medium or fluid in conduit 33 will decrease, thus decreasing therewith the 65 pressure in power element chamber 113, which under the inherent resilience of sealing means 109 and spring 110 will move trip member 47 to the left of Figs. 2 and 3. Upon attainment of substantially the desired low temperature at the 70 evaporator, the trip member 47 acting through lever 125 will have tilted the tube 117 counterclockwise of Fig. 2, breaking the circuit to the fan motor 21, and thus decreasing the rate of vaporization in the evaporator. The tube 117 75

will be tilted back and forth to make and break the motor circuit during the cooling cycle in response to variation within predetermined limits in the fluid characteristic transmitted to power element chamber 113, but due to the relative permitted movement between plunger 45 and its sleeve 46, the plunger member 45 will not actuate the lever means 56. When the absorbing or adsorbing power of the medium 15 in container 10 means 13 has been substantially satisfied, the pressure in conduit member 33 will continue to increase beyond the pressure which will start motor means 21, and regardless of the increased flow by the fan 25 of cooling air which will now 15 continue until the evaporator is again cooled down as above described. The limiting stop or nut 47 will take up the play between plunger 45 and sleeve 46, causing the abutment or ring member 49 to engage the cross pin or member 66. 20 Continuation of the movement of plunger 108 and 45 to the right of Figs. 2 and 3 will cause the ring member 49, backed up by leaf spring 52, to tilt from the normal to plunger 45 into biting or gripping relation to sleeve 46, as in Figs. 2 and 25 3. When the ring member 49 has been tilted and tightly grips the sleeve 46, then movement of plunger 45 to the right will act through this established positive engagement with lever means 56 to rotate or move the same clockwise about its 30 pivot pin 55, which will initiate the heating period. As above noted, the break point 80 between means 56 and spring 84 is very slightly above and overcenter, and therefore the movement of plunger 45 necessary to carry point 80 35 through center is very slight. As the point 80 crosses center, the compressed spring 84 will act with an increasing component to force the lever means 56 and arm 69 downward and clockwise about pin 55 into engagement with stop 68. The 40 downward movement of point 80 carries it across the line of points 81, 78, so that the spring 84 will react with an upward component on the lever 76, swinging the same clockwise of Fig. 2 about its knife edge fulcrum 78. The upward 45 movement of lever 76 is transmitted through link 79 to valve stem 41 to open valve 20 and permit fuel to flow to the main burner means 18. The fuel supplied to means 18 will be ignited by the pilot burner 21^a. Should it happen that the pilot 50 burner flame is insufficient to heat the bulb element 92, then the spring 90 will have acted through arm 85 to hold the valve member 40 on its port 39 against the lifting component of force of spring 84, and thus prevent flow of fuel to 55 the burner means 18. It is of course understood that the bulb element 92 and responsive means 91 comprise a safety device, which on failure, or substantial failure, of the pilot burner flame will act to close the valve 20 or to extinguish the main 60 burner means 18 and stop operation of the system. The downward movement of lever arm 69, as above described, acts through the rod 72 and linkage 12 to operate the damper means 11 to close the inlet openings 5, 5^a and the outlet openings 4, 4^a. The gases within casing member 1 which are heated by means 18, will rise over the 65 container means 13 and be forced by the running fan 25 to travel down the passages 6 and 8 for continuous recirculation and heating. During 70 the heating period, refrigerant medium in the vapor state will be driven off from the adsorbent or adsorbent medium within container means 13, and will pass through top header 14 to conduit member 16. The check valve 34 will direct the 75 flow through conduit member 28, past check valve

30, to the condenser B. The motor means 21 which is constantly energized during the heating period, will also drive fan 24, which will force cooling air upward over the condenser B to cool and liquefy the refrigerant medium supplied thereto. The liquefied medium will pass through the valve controlled conduit member 31 to the evaporator E, any surplus being stored in the receiver C until permitted by the flow control means D to enter the evaporator E via the conduit 10 member 32. When the recirculating gases within the housing member 1 have been heated to a predetermined degree, say, about 400° F., substantially all of the refrigerant medium will have been driven off from the adsorbent or adsorbent 15 medium 15 in container means 13 and have passed to the condenser B. Upon the temperature within the generator-absorber reaching the desired degree, the fluid within the bulb element 105^a of the responsive means will have acted upon 20 the resilient sealing means 101 to force plungers 102 and 97 and the lifting member 73 upward. As the lifting member 73 moves upward, the upper inclined edges of the arms 74 will engage the underside of cross-pin 66 and lift lever means 25 56 upward, or counterclockwise, about its fulcrum 55 against the force of spring 84, until point 80 crosses center, when spring 80 will snap the lever means 56 up against stop screw 68. During the latter part of the upward movement of lifting 30 member 73, the fingers 75 thereof will engage the ring member 49 and turn it back to substantially vertical position as it fulcrums on the leaf spring 52, and will then slide or move it toward the left of Figs. 2 and 3 against the force 35 of spring 52 and along sleeve 46, so that it will be out of the way of the cross-pin 66 and not stop or hinder upward movement of lever means 56. The valve 20 will be snapped closed by the force of spring 84 as point 80 passes through the 40 extended line of points 81, 78, which operation starts the cooling period in the cycle. The damper arm 69, which is moved upward with lever means 56, acts through rod 72 and linkage 45 12 to operate the damper means 11 to open inlet 50 openings 5, 5^a and outlet openings 4, 4^a, closing passages 6 and 8. The fan 25 will continue in operation, cooling the container means 13 and the atmosphere in passage 7. As the temperature in passage 7 decreases, the fluid in bulb element 105^a will contract, permitting spring 103 in the power element 99 to move connected plungers 102 and 97 and lifting means 73 downward to the position shown in Fig. 2, thus completing a 55 cycle of operation of the system and of the control device.

It may be noted that the spring 52 will return the abutment member 49 to the right along sleeve 46 to its operative location as the lifting means 73 and fingers 75 are retracted. It may also be noted that the cooperating sleeve 46 and annulus 49 permit a very sensitive operation as the annulus is operable to grip tightly the sleeve 46 anywhere within the length of the sleeve.

The above described cycle is descriptive of the 65 normal operation of the control device and system. However, upon initial operation or starting of the system with the evaporator substantially at room temperature, there may be several cycles during which the motor means 21 will operate 70 continuously, because the temperature of the evaporator E may not drop sufficiently in the first few cycles to permit spring 103 to retract plunger 45 far enough to the left to tilt tube 117 and break the motor circuit.

What I claim and desire to secure by Letters Patent of the United States is:

1. A control apparatus of the character described, comprising a movable control device, means responsive to a fluid characteristic, a pair of members cooperable with said means and with said device, one of said members having means movable relative thereto and normally establishing cooperable relation between said members whereby said responsive means may move said control device in one direction, and a second means responsive to a fluid characteristic and operable to engage one of said members to move said control device in the opposite direction, said second-named responsive means being operable to move said establishing means out of cooperable relation between said members when said second-named responsive means acts to move said control device.
2. A control apparatus of the character described, comprising a movable control device, lever means for actuating said control device, means responsive to a fluid characteristic and having a reciprocable member, means movable relative to said member and normally establishing engagement between said member and said lever means to move said control device in one direction, a second means responsive to a fluid characteristic and having means to engage and transmit movement to said lever means to move said control device in the opposite direction, and means operable to move said establishing means relative to said member to prevent opposition by said first-named responsive means to movement of said lever means when said second-named responsive means acts to move said lever means.
3. A control apparatus of the character described, comprising a movable control device, lever means for actuating said control device, means responsive to a fluid characteristic and having a reciprocable member for moving said lever means in one direction, an abutment member movable relative to said reciprocable member and normally having a position to transmit motion from said reciprocable member to said lever means, a second means responsive to a fluid characteristic and having means to engage said lever means to move said lever means in the opposite direction, and means actuated by said second-named responsive means to move said abutment member out of motion-transmitting position when said second-named responsive means acts to move said lever means.
4. A control apparatus of the character described, comprising a movable control device, means responsive to a fluid characteristic and having a reciprocable member, lever means for actuating said device, means carried by and movable relative to said member and having a normally operable position for engaging said lever means whereby to transmit motion from said responsive means to said device, and a second means responsive to a fluid characteristic and operable to engage said lever means to actuate said device, said second-named responsive means acting to move said movable carried means out of operative position upon movement of said lever means whereby to prevent opposition by said first-named responsive means to movement of said device.
5. A control apparatus of the character described, comprising a movable control device, means responsive to a fluid characteristic and having a reciprocable member, lever means for

actuating said device, means slidably carried by said member for engaging said lever means, means normally acting to maintain said slidable means rigid with said member whereby to transmit motion from said responsive means to said device, and a second means responsive to a fluid characteristic and operable to engage said lever means to actuate said device, said second-named responsive means acting to release said slidable means from said reciprocable member upon movement of said lever means whereby to prevent opposition by said first-named responsive means to movement of said device.

6. A control apparatus of the character described, comprising means responsive to a fluid characteristic, a thrust member operatively connected to said means for movement thereby, means opposing movement of said thrust member, switch means, means to transmit motion from said thrust member to said switch means whereby said responsive means is operable to make and break circuit at said switch means, a control device, and means to transmit motion from said thrust member to said control device whereby to operate said device, said last-named means being operable to move said motion transmitting means to actuate said switch without movement of said transmitting means being transmitted to said control device until said switch has been actuated.

7. A control apparatus of the character described, comprising means responsive to a fluid characteristic, switch means for controlling an electric circuit, a control device movable to two positions, and means operable by said responsive means to actuate said switch means and said device, said last-named means being operable to actuate said switch means to circuit making and to circuit breaking positions irrespective and independently of actuation of said device and to actuate said device to each of said positions independently of actuation of said switch means.

8. A control apparatus of the character described, comprising a movable control device, power means responsive to a fluid characteristic, a pair of members cooperable with said means and said device, an abutment member movable relative to said members and operable to transmit movement from one of said members to the other of said members whereby said power means is operable to move said control device in one direction, and a second power means responsive to a fluid characteristic and operable to move said control device in the opposite direction, means resisting movement of said device in said opposite direction, said second-named power means acting to move said abutment member out of motion transmitting position and to overcome said resisting means whereby said second-named power means can move said control device.

9. A control apparatus of the character described, comprising a movable control device, power means responsive to a fluid characteristic, a pair of members cooperable with said means and said device, an abutment member movable relative to said members and operable to transmit movement from one of said members to the other of said members whereby said power means is operable to move said control device in one direction, a second power means responsive to a fluid characteristic and operable to move said control device in the opposite direction, means resisting movement of said device in said opposite direction, said second-named power means acting to move said abutment member out of

motion transmitting position and to overcome said resisting means whereby said second-named power means can move said control device, electrically energized means, a switch controlling said electrically energized means, and means operatively connecting said first-named power means and said switch.

10. A control apparatus of the character described, comprising a movable control device, power means responsive to a fluid characteristic, a pair of members cooperable with said means and said device, an abutment member movable relative to said members and operable to transmit movement from one of said members to the other 15 of said members whereby said power means is operable to move said control device in one direction, a second power means responsive to a fluid characteristic and operable to move said control device in the opposite direction, means resisting movement of said device in said opposite direction, said second-named power means acting to move said abutment member out of motion transmitting position and to overcome said resisting means whereby said second-named power means can move said control device, a third power means responsive to a fluid characteristic, and means for transmitting motion from said third-named power means to said control device, said third-named power means being 30 operable to move said control device to or to hold said control device in given position irrespective of operation of said first-named or said second-named power means.

11. A control apparatus of the character described, comprising a movable control device, power means responsive to a fluid characteristic, a pair of members cooperable with said means and said device, an abutment member movable relative to said members and operable to transmit movement from one of said members to the other of said members whereby said power means is operable to move said control device in one direction, a second power means responsive to a fluid characteristic and operable to move said control device in the opposite direction, means resisting movement of said device in said opposite direction, said second-named power means acting to move said abutment member out of motion transmitting position and to overcome said resisting means whereby said second-named power means can move said control device, a control means, and means operatively connecting said control means to one of said cooperable members for movement thereby.

12. A control apparatus of the character described, comprising a movable control device, lever means for actuating said control device, means responsive to a fluid characteristic and having a reciprocable member for moving said lever means in one direction, an abutment member movable relative to said reciprocable member and normally having a position to transmit motion from said reciprocable member to said lever means, a second means responsive to a fluid characteristic and having means to engage said lever means to move said lever means in the opposite direction, means actuated by said second-named responsive means to move said abutment member out of motion-transmitting position when said second-named responsive means acts to move said lever means, a switch movable to open and closed positions, and means operatively connecting said reciprocable member and said switch.

13. A control apparatus of the character described, comprising a movable control device,

lever means for actuating said control device, means responsive to a fluid characteristic and having a reciprocable member for moving said lever means in one direction, an abutment member movable relative to said reciprocable member and normally having a position to transmit motion from said reciprocable member to said lever means, a second means responsive to a fluid characteristic and having means to engage said lever means to move said lever means in the opposite direction, means actuated by said second-named responsive means to move said abutment member out of motion-transmitting position when said second-named responsive means acts to move said lever means, a switch movable to open and closed positions, means operatively connecting said reciprocable member and said switch, a control means, and means operable by said reciprocable member to actuate said control means.

14. A control apparatus of the character described, comprising a movable control device, lever means for actuating said control device, means responsive to a fluid characteristic and having a reciprocable member for moving said lever means in one direction, an abutment member movable relative to said reciprocable member and normally having a position to transmit motion from said reciprocable member to said lever means, a second means responsive to a fluid characteristic and having means to engage said lever means to move said lever means in the opposite direction, means actuated by said second-named responsive means to move said abutment member out of motion-transmitting position when said second-named responsive means acts to move said lever means, a switch movable to open and closed positions, means operatively connecting said reciprocable member and said switch, a control means, means operable by said reciprocable member to actuate said control means, a third means responsive to a fluid characteristic, and means operable by said third-named responsive means to actuate said control device irrespective of operation of said second-named responsive means.

15. A control apparatus of the character described, comprising a control device movable in opposite directions, snap-acting means to move said device and including a lever, means responsive to variation in a fluid characteristic, means for transmitting motion from said responsive means to said lever to snap said device in one direction, a second means responsive to variation in a fluid characteristic, means for transmitting movement from said second-named responsive means to said lever to snap said device in the opposite direction, and means supported by and movable relative to one of said transmitting means to operatively connect one of said transmitting means to said lever, the other of said transmitting means acting to move said connecting means out of operative relation to said one transmitting means whereby said other transmitting means can move said lever.

16. A control apparatus of the character described, comprising a movable control device, means responsive to a fluid characteristic, a pair of members cooperable with said means and with said device, one of said members having means movable relative thereto and normally establishing cooperable relation between said members whereby said means may move said control device in one direction, a second means responsive to a fluid characteristic and operable to engage one of said members to move said con-

5 trol device in the opposite direction, said second-named responsive means being operable to move said establishing means out of cooperable relation between said members when said second-named responsive means acts to move said control device, a movable switch means, and means operable by said first-named responsive means to actuate said switch means.

10 17. A control apparatus of the character described, comprising a movable control device, means responsive to a fluid characteristic, a pair of members cooperable with said means and with said device, one of said members having means movable relative thereto and normally establishing cooperable relation between said members whereby said means may move said control device in one direction, a second means responsive to a fluid characteristic and operable to engage one of said members to move said 15 control device in the opposite direction, said second-named responsive means being operable to move said establishing means out of cooperable relation between said members when said second-named responsive means acts to move said control device, a movable switch means, and means to actuate said switch means, said one member having means cooperable with said actuating means whereby said first-named responsive means is operable to actuate said switch means.

20 18. A control apparatus of the character described, comprising a control device movable in opposite directions, means responsive to a fluid characteristic for moving said control device in one direction, safety means for moving said control device in the opposite direction, lost-motion means operatively connecting said responsive means and said control device whereby said safety means is operable to actuate said control device without opposition by said responsive 25 means, a second means responsive to a fluid characteristic, and means operatively connecting said second responsive means and said control device whereby said second responsive means is movable to move said control device in said opposite 30 direction.

35 19. A control apparatus of the character described, comprising a control device, means responsive to a fluid characteristic, an operating means interconnecting said responsive means and said control device, a second control device, means operatively connecting said operating means and said second control device, an operating arm movable by said operating means and operable to actuate a control means, a second means responsive to a fluid characteristic, means operatively connecting said second responsive means to said first-named control device and to said arm, and safety means responsive to a fluid characteristic and operable to actuate said first-named control device.

40 20. A control apparatus of the character described, comprising a control device, means responsive to a fluid characteristic, an operating means interconnecting said responsive means and said control device, a second control device, means operatively connecting said operating means and said second control device, an operating arm movable by said operating means and operable to actuate a control means, a second means responsive to a fluid characteristic, means operatively connecting said second responsive means to said first-named control device and to said arm, safety means responsive to a fluid characteristic and operable to actuate said first-named control device, and lost-motion means interposed

5 between said operating means and said first-named control device whereby said safety means is operable to actuate said first-named control device without opposition by said first-named responsive means.

10 21. A control device of the character described, comprising means responsive to a fluid characteristic, switch means for controlling an electric circuit, a control device, a motion transmitting member operable by said responsive means for actuating both said switch means and said control device, and a releasable operating member for establishing operative connection between said motion transmitting member and said control device after actuation of said switch means by 15 movement of said motion transmitting member in one direction whereby said switch means and said control device are actuated independently of each other.

20 22. In a control apparatus of the character described, a movable controlling means, a movable controlling means for controlling operation of said first-named controlling means, said second-named controlling means having operative connection with said first-named controlling 25 means, said first-named controlling means being moved toward one position when said second-named controlling means is moved in one direction and being moved toward a second position when said second-named controlling means is 30 moved in an opposite direction, means responsive to a fluid characteristic and operable to move said second-named controlling means in one direction, releasable means movable relative to said responsive means and operable to establish connection between said responsive means and said second-named controlling means so that said responsive means can move said second-named controlling means, a second means responsive to a fluid characteristic for moving said second- 35 named controlling means in the opposite direction, and means operable to move said releasable means relative to said first-named responsive means to disengage said first-named responsive means and said second-named controlling means 40 to prevent opposition by said first-named responsive means to movement of said second-named controlling means by said second-named responsive means.

45 23. In a control apparatus of the character described, a movable controlling means, a movable lever member for controlling operation of said controlling means, said controlling means and said lever member being arranged so that said controlling means will be moved to one position when said lever member is moved in one direction and will be moved to a second position when said lever member is moved in the opposite direction, means responsive to a fluid characteristic and operable to move said lever 50 member in said one direction, a second means responsive to a fluid characteristic and operable to move said lever member in said opposite direction, means movable relative to said responsive means and operable upon movement of said responsive means in one direction to establish connection between said lever member and said first-named responsive means so that said first-named responsive means can move said lever 55 member to move said controlling means, and means operable to disengage said first-named responsive means and said lever member to prevent opposition by said first-named responsive means to movement of said lever member when said 60

second-named responsive means acts to move said lever member.

24. In a control apparatus of the character described, a reciprocal valve member for controlling flow of a fluid, a lever member controlling operation of said valve member, said valve member and said lever member being arranged so that said valve member is moved to closed position by movement of said lever member in one direction and moved to open position by movement of said lever member in the opposite direction, power means responsive to a fluid characteristic and operable to move said lever member in said one direction, said power means having a movable member, means movable relative to said movable member and operable to releasably establish connection between said movable member and said lever member so that said power means can move said lever member, power means responsive to a fluid characteristic for moving said lever member in said other direction, said second-named power means having a movable member for moving said lever member, means operable to move said releasable connecting means relative to the movable member of said first-named power means to disengage the movable member of said first-named power means and said lever member to prevent opposition by said first-named power means to movement of said lever member when said second-named power means acts to move said lever member, and yieldable means acting to maintain engagement between the movable member of said first-named responsive means and said lever member.

25. In a control apparatus of the character described, a valve for controlling flow of fuel to a burner, a snap-acting lever for actuating said

valve, means responsive to variation in a fluid characteristic and controlling movement of said valve toward open position, means responsive to variation in a second fluid characteristic and controlling movement of said valve toward closed position, cooperable motion transmitting members for positively transmitting the force of said first-named responsive means to said lever, means operable to hold one of said transmitting members in position for engagement with the other of said members upon operation of said first-named responsive means, said second-named responsive means being engageable with said lever for positively moving said lever, and means to move said transmitting members out of engaging relation such that said first-named responsive means will not oppose operation of said lever by said second-named responsive means.

26. A control device comprising a supporting structure including a valve casing, a valve member movably supported in said casing, a lever cooperable with and controlling the operation of said valve member, a spring engaging said lever and movable over-center to move said lever with a snap-action, a pressure responsive element carried by said structure, a plunger rod extending from and movable by said element, a pair of cooperable members for transmitting motion from said rod to said lever, one of said cooperable members being carried by said lever, the other of said cooperable members being movable by said rod, a leaf spring having one end fixed to said structure and being engageable with one of said cooperable members to hold said cooperable members in motion transmitting engagement on movement of said rod.

EARNEST J. DILLMAN.
